LAUNDRY APPLIANCE

Hart A. Stoddard, Westport, Conn.

Application April 10, 1936, Serial No. 73,718

5 Claims. (Cl. 38—141)

This invention relates to laundry equipment, and, more particularly, to water-reservoirs of the capillary feed type as employed usually in commercial laundries for moistening clothes for hand application when required to so-called "wet spots" as these are noted on articles being laundered by the attendant at a mangle or other ironing machine or device while such articles are being made ready for ironing or are being ironed.

10 Devices of this kind essentially include a container in which water is to be stored, and a cover for such container the purpose of which is to support a water absorbent element or copper, this last capillary maintained wet or moist by a fabric adjunct in the form of a wick-means depending from the copper and dipping into the water in the container; such cover being removable to permit replenishment of the water supply as and when required.

20 These containers are given a mounting such that they will be held against accidental overturning, as spilled water in a commercial laundry more often than not is more or less of a profit-consuming catastrophe; this mounting being such that the container can be moved to and from a handy position near the ironing appliance.

To attain both these objectives, said devices are commonly carried by a ring support at the free end of a pivoted and substantially horizontal swing arm, so that the container and its carried parts can be swung out, from a hidden or out-of-the-way position, for wetting or moistening of the spotting cloth when required. Normally, however, the device is in its out-of-the-way position, since space is at a premium in a commercial laundry. Said arm is generally pivotally mounted so as to be swung to move the device from a normal position under a table, shelf or the like, as one for supporting laundered articles, to a utilizable position beyond such table, and vice versa, but during such swinging always to have the top of the container at a height very close to the under surface of said table. As a result of this last necessity or practice, carelessness of the attendant often results in knocking loose the cover and the parts carried thereby, to wit, the wet copper and its wet wick-means, from the container. This happens when the attendant, after inadvertently leaving the spotting cloth on the copper on the top of the container, swings the pivoted arm which supports the container to its hidden position. Then the edge of the table acts as a wiper element to engage the spotting cloth, with the result that as the container is snapped with its swinging mount under the table, the loose

5 container top, the copper and the wick-means are torn loose from the container and fall to the floor. When this happens, the fabric parts are dirtied and rendered unfit for further use.

10 One of the objects of the present invention is to provide a container so constituted as to include the essential elements above referred to, but one so constructed that the attendant can, inadvertently, or deliberately and for greater convenience, leave the spotting cloth on the top of 15 the device, and yet any chance of an accidental breaking down of the device, such as just described, is absolutely avoided, when the swinging mount is thrust in under the table.

According to the present invention, this object 15 is attained by providing the cover as a substantially cylindrical cup telescoped substantially wholly within, and resting by gravity on a rim or shoulder portion of, a substantially cylindrical container, and by making such cup of sufficient 20 depth to accommodate the spotting cloth therein without projection of other than negligible portions of the latter above the top rim of the cup; while securing the swinging mount to its pivot at such a level, or shaping said mount in the direction of its extension between said pivot and the portion thereof which carries the container, 25 that when the latter is swung in under the table the top mouth of the cup is at a height very close to the under surface of the table.

30 Further, in devices of the kind to which the present invention relates, frequent replenishment of the water in the container is required. As aforesaid, this is accomplished by removal of the cover for the container. Thus, since the copper 35 is secured at the upper surface of the cover, and the wick-means depends below the cover, a time-consuming annoyance heretofore has been the difficulty of properly yet quickly entering the wick ends into the container incident to replacing the cover thereon following a replenishment 40 of the water in the container. This has followed from the fact that the wick-means heretofore employed has comprised a plurality of wicks, usually four, 90° apart, spaced around the container top close to the periphery thereof. Such 45 a large array of individual wick elements, and their placement for limp dangling extremely near the peripheral points on the cover has been deemed essential to obtain proper capillary action and to maintain the central part of the copper in a desired degree of wetness regardless of a steadily falling water level in the container.

50 Another object of the present invention is to provide a combined copper and wick-means there- 55

- for which as a composite entity shall be simpler than that above described, and shall be fabricable at a very low cost and hence practicably frequently renewable, and which, at the same 5 time, will not only avoid the cover replacement difficulty alluded to above, but will act with the required efficiency in maintaining the copper in a desired degree of wetness regardless of varying water levels in the container.
- 10 According to the invention, this object is attained by providing merely a single substantially central hole in the bottom wall of the cup aforesaid, by providing a single substantially circular fabric sheet, of one or plural ply thickness, as the copper, and by providing a single fabric wick-means in the form desirably of a looped fabric strip the central looped portion of which is suitably secured, preferably by stitching, to approximately the center of said sheet for 15 dependence of the two lengths of such strip in mutually close dangling relation below the cup after protrusion downwardly through said hole.
- Where a plurality of widely separated wick elements are employed, as has heretofore been 20 deemed necessary in order to give even wetness to the copper, the very object thus in mind has been defeated. These wick elements have usually been the terminal lengths of strips of fabric material the central portions of which are laid 25 on the top of the cover between diametrically opposite slots near the periphery of the latter. When four such wick elements are employed, there are present two strips, the central portions of which provide the copper. These central portions usually cross the top of the cover 30 at right angles so as to provide a cruciform copper which is of two-ply thickness where the central lengths of the strips cross each other at the center of the cover, but which is elsewhere of 35 single-ply thickness. In such an arrangement, further, the central portions of the two strips are apertured to clear loosely an upstanding knob at the center of the cover provided for lifting away of the latter when water is to be replenished in the container. As a result, the spotting 40 cloth has to be applied to parts of the copper within the annular space between the periphery of the cover and said knob, and further, usually, partially to the one-ply divergently separating 45 portions of the copper and partially to the two-ply portion thereof immediately surrounding the knob. Thus, a given pressure and time of contact of the spotting cloth against the copper cannot be depended upon always to give the intended 50 degree of wetness to the spotting cloth. Moreover, I have found that when a plurality of widely spaced wick elements are employed to serve the copper, the object in mind, e. g., an even wetting of the copper, is hindered rather than 55 helped; despite the fact that, in the hope of attaining this object, the disadvantage is tolerated of having these wick elements very close to the periphery of the cover. This last mentioned disadvantage, as hereinabove indicated, 60 lies in the fact that with the wick elements thus arranged, it is troublesome and time-consuming to replace the cover on the container each time the latter is refilled with water, which refills 65 must occur at fairly frequent intervals. With such a wick arrangement, it is difficult to maintain the wick elements of equal lengths as they depend from the cover at different points around the periphery of the latter, with the result that 70 75 when the water level falls sufficiently in the con-

tainer, one or more of said wick elements may be capillary idle.

The invention will be more clearly understood, and the above and other advantages thereof will be appreciated, from the following description of a now preferred but merely an exemplifying embodiment of the invention as shown in the accompanying drawing, in which:

Figure 1 is a top plan view thereof, partially broken away; and

Fig. 2 is an axial section.

Referring to the drawing in detail, the container is indicated at 5, the cover at 6, the copper at 7, and the wick-means at 8.

The container 5, wherein a supply of water is indicated at W, is shown as having a plane horizontal bottom wall 5a, a cylindrical side wall 5b and an outwardly extending flange 5c running all around the top of the wall 5a to provide at its upper limit an annular seat surrounding the upper end or mouth of the container.

The cover 6 is not a mere disk, but, on the contrary, is itself also a true container in the form of an open topped cup. As shown, this element, herein called the cover, has a plane horizontal bottom wall 6a, a cylindrical side wall 6b, and an outwardly extending flange 6c running all around the top of the wall 6a to provide at its upper limit an annular extension for resting on the annular seat provided by the flange 5c of the container.

Thus, when the parts are assembled as shown best in Fig. 2, the cover 6 rests on the container 5 merely by gravity, but with the receptacle part of the cover telescoped within the receptacle part of the container. The outer diameter of the flange 6c of the cover is slightly greater than the outer diameter of the flange 5c of the container, so that, even if the cover happens to be centered within the container as illustrated, the cover is instantly removable from the container by lifting, upon applying finger pressures against the two flanges spannably of the top of the device.

The copper 7 is shown as a circular piece of suitable fabric, as a medium-weight terry cloth, of uniform thickness all over and laid flat against the horizontal upper surface on the bottom wall 6a of the cover.

Said wall, centrally thereof, is provided with a round hole 6d; which hole is for the accommodation of a connection of the copper with the wick-means 8.

Such connection is, as here illustrated, made by way of a circular line of machine stitching 9. Thereby, at the center of the circular copper, a circular area of the wick-means 8 is laid in capillary operative contiguity with a circular area of the copper, the boundary of which area is concentric with the periphery of the copper. Thus, all water elevated by the single wick-means from the water collection 9 will be delivered to the copper centrally thereof and in such manner as to insure uniform water dispersion radially of the copper all around the same so as always to maintain the copper uniformly moist all over.

The wick-means 8 is shown as in the form of a single strip of fabric, as a medium-weight terry cloth. This single wick element is at the center of its area stitched, as just above described, to the copper, so as to present two wick lengths depending below the bottom of the cover 6, at a central point on such bottom, while the copper lies on the upper surface of the wall 6a of the cover.

When the parts are assembled as shown in Fig. 2, the wick-means 8 will establish itself in some such way as there illustrated. Regardless, however, of how the wick-means settles itself 5 in the water collection W, the supply of water to the copper will always be the same; and this will also be true, regardless of how far the water level falls, up to the point where any part of the wick element can continue to take up the required 10 amount of water.

When the water collection W falls so much that replenishment thereof is required, the cover is merely lifted up and away as described; and as soon as the container has again been supplied 15 with water, the cover is always easily and instantaneously replaced, due to the generally vertical dangling of the wick-means below the center of the copper.

When the spotting cloth (not shown) is accidentally or deliberately left on the copper, such cloth will be substantially wholly housed in the receptacle part of the cover, so that no accidental engagement of such cloth or any part thereof with another object can possibly result in knocking 20 loose the cover and its carried copper and wick-means.

When replacement of the copper and wick means is desired, the entity including these elements is removed from the cover merely by manually ruffling and grasping the copper, and pulling the same upwardly, the wick-means then being drawn up through and free of the hole 6d in the bottom of the cover. The substitute entity, preferably such in order to insure that the stitching together of the copper and the wick-means can be performed with maximum convenience and minimum cost, is mounted on the cover merely by first pulling the two lengths of the wick-means 30 downwardly through said hole 6d, and then patting the copper down flat.

Variations and modifications may be made within the scope of this invention, and portions of the improvements may be used without others. 40

45 I claim:

1. In a device of the kind described, the combination of an open topped water container; a cover therefor in the form of an open topped cup of considerable depth and of a cross section to permit telescoping the cup downwardly within the 5 container; means partially carried by the container and by the cup for allowing the cup to rest by gravity on the container when thus telescoped therein, the cup being of less depth than the container whereby when the cup thus 10 rests on the container the bottom of the cup is considerably above the bottom of the container; a fabric copper in the bottom of the cup of substantially uniform capillary action all over; and a single wick secured to substantially the 15 center of the copper for dependence therebelow, the bottom wall of the cup having a substantially central hole therein below which said wick depends.

2. A device as in claim 1, wherein said copper 20 is substantially circular, and said wick is a strip of fabric having a circular area thereof stitched to substantially the center of the copper.

3. A device as in claim 1, wherein said copper is substantially circular, and the wick-means is 25 a strip of fabric secured at a substantially central point to substantially a central point on the copper, and wherein such securement is a substantially circular line of stitching through the copper and the wick, said line being substantially 30 concentric with the circular boundary of the copper.

4. A device as in claim 1, wherein said means includes a ledge element on the container near the top thereof and an engaging projection on 35 the cup near the top thereof, whereby when the cup is telescoped within the container the top of the cup is at substantially the same level as the top of the container.

5. A device as in claim 1, wherein the wick is 40 secured to the copper by a single substantially circular line of stitching, and said hole is substantially circular and of greater diameter than the diameter of said line.

HART A. STODDARD. 45
